to Vistron Corporation, Cleveland, Ohio

Filed Sept. 3, 1971, Ser. No. 177,917

Term of patent 14 years

Int. Cl. D4—02

U.S. Cl. D4—24

FIG. 1 is a perspective top view of the tooth stain-remover tip showing my new design;

FIG. 2 is an elevational view taken from one end thereof;

FIG. 3 is a top plan view thereof;

FIG. 4 is a side plan view;

FIG. 5 is an elevational view taken from the end opposite that in FIG. 2; and

FIG. 6 is a side sectional view taken along the line 6—6 in FIG. 3.

The broken line representation of a toothbrush is for purposes of illustration only.

I claim:

The ornamental design for a tooth stain-remover tip for toothbrushes and the like, as shown and described.
